COKING RETORT OVEN WITH LINER WALLS OF TWO THICKNESSES

Linwood G. Tucker, Jr., Pittsburgh, Pa., assignor to
Koppers Company, Inc., a corporation of Delaware
Filed Apr. 20, 1961, Ser. No. 104,280
6 Claims. (Cl. 202—139)

The present invention relates in general to improvements in the liner wall structure of horizontal coke oven batteries of the general type of H. Koppers U.S. Patent No. 818,033, in which the heating walls are arranged side by side in a row, in alternation with intervening coking chambers, with each heating wall constituted to a single row of vertical combustion flues extending crosswise of the battery, for simultaneous heating of both the coking chambers along each side of the heating walls. In such coke oven batteries, it is now, and for a long time has been, customary to make the heating walls and the oven chamber top and bottom walls of silica brick with highly silicious mortar joints, as explained in Rueckel U.S. Patent No. 2,393,658 of January 29, 1946, and to standardize the thickness of the liner walls in the range 3" to 5" thickness.

However, due to the lateral pressure that might be exerted on the liner walls by the coal charges in the coking chambers, and the load imposed on said walls, as a result of loaded larry cars running on rails along the battery roof, the liner walls have been, in practice, limited to 4" and 5" walls, to insure against damage to the structure for the normal life expectancy of such commercial ovens.

Coke oven builders have continually been looking for ways to increase the throughput of coke ovens and yet retain the features of the structure by virtue of which they have lasted long enough to carbonize in some cases three to four hundred thousand tons of coal per oven. Any increase in coking rate will reduce the initial investment that steel producers will be called upon to make per unit of coke and hence per unit of steel produced. The steel industry will be very receptive to a method of this type which will enable them to reduce the cost of coke in new batteries of coke ovens built for increased production as well as for batteries built to replace worn out or obsolete units.

One method of increasing the coal carbonizing rate of coke ovens is to increase the rate of heat transfer through the oven walls. With the present design of ovens, the limiting factor in regard to heat transfer is the restricting temperature that can be carried in the combustion chambers. The rate of heat transfer can be increased by designing thinner wall brick liners, but if liners are made thinner than 4", the strength of the oven wall is reduced, making this attack impractical.

The primary object of the invention is the improvement of the liner wall structure of these vertical flues in a manner providing for heat transfer therethrough at the faster rate corresponding, for instance, to that of a 3" wall, as compared with a 4" thick wall, or a 4" wall as compared with a 5" wall, but which provides additional structural strength to such walls corresponding to that afforded by a 4" and 5" thick wall respectively. More particularly, the aim of the invention is to provide a mode of construction of such heating walls meeting the long-sought desire, and satisfying the present urgent demand for an increase in the rate of coking to increase the coking capacity of oven chambers, in a manner retaining the single row vertical combustion flue type of heating walls for safe coking operation in coke oven batteries as aforesaid, by providing them with liner walls having the faster heat transfer rate available with

2

a thinner liner wall of a thickness of 3" to 4", but with the strength of walls of 4" to 7" thickness.

In accordance with the present invention, it is believed that the rate of heat transfer can be safely increased while strengthening the wall structure by designing the brickwork with protruding liner portions, as illustrated in the drawings, utilizing 2½ to 4½" brick in alternate courses, layers or strata and 5 to 8" brick in the intermediate courses, layers or strata of the liner walls, between and joined to the brick in the tie walls. Actually, the strength of the wall as a whole should be increased as a result of the novel design, because of the strong ceramic bond that will be obtained between the mortar and the brickwork of the protruding portion of the liners. This type of strong ceramic bond is observed during the tear down of old batteries. The bottle brick for air and gas at the base of the heating flues that have been heated to the higher temperatures are strongly bonded together whereas the liner brick are very weakly bonded. Also the bottle brick appear to be stronger because of the higher temperatures. The non-protruding liners in the present invention should also be more strongly bonded than with the conventional non-protruding liners because a larger percentage of the area of the mortar joints will be heated to the higher temperature. For example, assume the oven wall is made up of liners 3" and 5" thick, alternately spaced up the entire height of the vertical flue. The 5" liner would project 2" within the flue. Therefore, this entire projection should approach the temperature of the flue surface side of the 3" liner. It would be unwise to make this projection much greater than 2" because it would then interfere with the combustion and flow of gases up the flue and therefore it would not approach the temperature level of the "hot side" of the 3" liner. Because the entire projecting portion of the liner approaches the temperature of the 3" liner the heat transferred through the wall would be about the same as if all the liners were 3" in thickness.

The entire exposed portion of the wider 5" liners would be raised to the maximum flue temperature. Under these conditions, the brick not only would have its maximum strength because of its crystalline structure change but the brick and mortar will be bonded firmly at these temperatures. Because a larger portion of the oven wall brickwork has been strengthened and bonded due to this elevated temperature, the oven wall is naturally stronger. Based on these facts the strength of a wall of this design would be stronger than a 4" wall of uniform liner thickness. So, too, with a liner wall formed of 4 and 5" or 4 and 6" wide bricks in alternate courses.

Assuming a liner wall is built in whole or in part of alternate 3" and intermediate 5" liners as illustrated in FIGURES 1 and 2, practically the entire protruding section of the 5" liner would be at a temperature approaching the airport brick. Based on this assumption, the vertical isotherm should be similar to the one illustrated in FIGURE 3, which indicates a liner wall of this design should have a heat transfer rate equivalent to a conventional wall that is slightly over 3" thick. Studies have been made and data obtained which show that the coking rate can be increased substantially by reducing the average liner wall thickness from 4½ inches to 3 inches.

In general it is recognized that all heating walls of all coke ovens are not built exactly because many must contain certain design features that reduce the rate of heat transfer in order to strengthen the walls which are expected to also be affected by factors such as the carbonization pressure of specific coals that are to be carbonized and other variables. In practice, the thickness of the liner walls has usually been limited to 4" and 5" liner walls,

as it has been generally agreed that any substantial part of a liner wall of 3" thickness would weaken the wall to a point where the life expectancy of the structure would be shortened, or the coals that could be used, or the operating rates and procedures, would be limited. These 4" and 5" liner walls reduce the coke capacity of the coke-producing unit, although it is recognized that if substantial parts of the liner wall could be built with a thickness of, say, 3", the heat transfer would be appreciably improved.

By embodying the principles of the present invention, a substantial proportion, as illustrated in the drawings, of the liner wall can be built with a thickness of 3" without sacrificing the strength of the wall, even though the remaining tiers or courses may be, although not necessarily, thicker than is conventional. Actually, the strength of the wall will be increased because of the strong ceramic bond between the mortar of the protruding portions of the liner brick and the bricks adjoining them in the tie walls.

In accordance with the present invention, the heating walls of coking chambers are built in the customary manner of silica brick masonry in tiers or courses with silica mortar joints to form oppositely disposed liner wall portions and transverse tie wall portions but with the alternate tiers of brick of a thickness between 2½ and 4½ inches and the intermediate tiers of brick 5" to 8" thick so that a portion of 2½ to 3½ inches protrudes into the flue chamber and extends from one tie wall to the next tie wall. With this arrangement, the heat of the gases in the flue bonds the protruding portions to the adjacent brick in the tie walls as well as to adjacent bricks in the liner walls to form a strong ceramic bond as mentioned aforesaid. The protruding portions should not exceed 2½ to 3½ inches, since otherwise the heat transfer rate through the thicker brick would not correspond with the rate of heat transfer through the thinner brick in the alternate tiers or courses. Thus, the measure of protrusion is limited to that extent to which the protruding brick will have the same rate of heat transfer as the thinner liner wall portions. Such a wall then will have the average strength of a 4 to 7 inch wall with a rate of heat transfer of a 3 to 4 inch wall.

This type of wall structure is especially suitable to use with the three most generally used types of heating walls now most generally used in the building and operating of horizontal coking retort ovens in the United States as well as in many foreign countries.

In addition to the features recited above, the invention has for further objects such other improvements and advantages in construction, arrangements, and operation hereinafter described and claimed.

The features of faster coking with the liner wall structure according to the present invention is best performed, and therefore carried out in its preferred form, in the manner of Patent No. 2,447,837 of 1948, of Joseph Becker, in conjunction with the flue bottom regulation of his Patent No. 2,100,762, in order to retain and accentuate the advantages of low pressure differential around the heating flue system that accrues with the greater freedom from counterflow conditions of its cross-over system, with the uniform coking afforded in conjunction with the faster coking of the present invention.

The novel features of the invention, however, are not limited in all their aspects to conjoint use with the aforesaid features, since the novel features are equally applicable to other types of heating flue systems, such as the twin flue, double divided, high and low burner flues, or other flued systems, such as that of Koppers Patent No. 818,033, Totzek Patent No. 1,782,638, and Otto Patent No. 2,665,442. For convenience, the present description of the invention will be confined to use of the invention in ovens of the type described in said patents.

The accompanying drawings, forming a part of this specification, show for purposes of exemplification, a preferred form and manner in which the invention may be embodied and practiced in the ovens of said patents, but

the invention is not to be limited to such illustrative instance or instances.

FIGURE 1 is an enlarged horizontal sectional view of coke oven flues and flue wall taken on the line I—I of FIGURE 2;

FIGURE 2 is a vertical cross-sectional view taken on the line II—II of FIGURE 1;

FIGURE 3 is a diagrammatic isotherm view of oven-flue wall;

FIGURE 4 is a view showing a vertical section taken longitudinally through a horizontal coke oven battery of the Becker type of the aforesaid Patent No. 2,100,762, and provided with the present liner wall improvement of their coking chambers and heating walls;

FIGURE 5 is an enlarged horizontal view taken on the line V—V of FIGURE 4 and showing the heating flues and structural detail of the masonry of one heating wall;

FIGURE 6 is an enlarged view of a fragment of the heating wall of the coke oven of FIGURE 3 and showing the disposition of the mortar and the bricks of the masonry;

FIGURE 7 is a vertical sectional view through one of the heating walls and adjacent coking chamber of the type of Koppers Patent No. 818,033, with the brickwork of Totzek U.S. Patent No. 1,782,768, the view being taken on the line VII—VII of FIGURE 8;

FIGURE 8 is a plan section taken on the line VIII—VIII of FIGURE 7;

FIGURE 9 is a plan view of an intermediate course B as shown in FIGURE 7;

FIGURE 10 is a plan view of an alternate course A as shown in FIGURE 7;

FIGURES 11 to 14 are views similar to FIGURES 7 to 10, illustrating the Wilputte type of oven with brickwork of the type of Otto U.S. Patent No. 2,665,242;

FIGURES 15 to 18 are views similar to FIGURES 7 to 10 but illustrating the Otto type of oven with the brickwork of the same Otto Patent No. 2,665,242.

The same characters of reference designate the same parts in each of the views of the drawings.

In the embodiments illustrated in FIGURES 1 to 6 of the drawings, the invention is incorporated in a combination Koppers-Becker coke oven battery; that is, a battery having provision for being fired alternatively with an extraneously derived relatively lean gas, such as producer gas and blast furnace gas, or with a relatively rich gas such as coke oven gas. For convenience, the present description will be confined to the present illustrated embodiment of the invention in such a combination oven battery; features of the invention may be applied, however, to other structures, for example, to ordinary so-called coke ovens fired with coke oven gas, or ordinary so-called "gas ovens" fired with producer gas or blast furnace gas; hence, the invention is not confined in its scope to the combination oven or to the specific use and specific embodiment in a cross-over flue type oven herein described as an illustrative example.

As the present improvements are useful with various types of coking retort ovens such as those shown in FIGURES 7 to 18, and as the details of such ovens may be readily understood by reference to the aforesaid patents which are made a descriptive part hereof, a brief description of the various parts of an oven battery that are concerned with the present improvements will suffice for an understanding of the same.

In general, a coking retort oven battery comprises high and narrow coking chambers 10 tapered as shown in FIGURE 5 to increase in width from one horizontal end 10a, at which a pusher ram is inserted, to the opposite horizontal end 10b, at which the coke is discharged out of the oven chambers, and are provided as usual with coke oven doors (not shown) at these opposite ends.

Heating walls 11 are provided on two opposite sides of the oven chambers 10 throughout the length and height

of the same, and the heating walls 11 are constituted of combustion flues 12 for flame heating charges in the adjacent chambers.

The heating walls 11 are formed of refractory silica brickwork and each comprise liner walls 13 on opposite sides thereof disposed between the vertical combustion chamber spaces 12 in the heating walls 11 and the coking chamber space of the chamber 10 in the form of a slot intermediate the heating walls.

The liner walls form the side faces of the coking chambers 10 and conduct the heat from flames of combustion in the vertical combustion flues 12 formed by the tie walls 20 directly into coal charges in the oven chambers 10 laterally inwardly of their mass from the two opposite sides thereof.

The heating walls 11 are constructed in general parallelism with each other and heretofore the liner walls 13 were constituted of the same thickness in any horizontal plane throughout the length of the coking chambers 10, usually of 4" or 5" thick bricks. Conventionally the upper and lower portions of these liner walls are backed up with thicker brickwork 14 than the rest of the liner wall bricks 13 to prevent overheating of the parts of the chambers 10 alongside the region of ignition in the base 15 of the combustion flues and in the region alongside the crown space 16 where the distillate gas flows along the top charge of coal during coking, and in such case the brickwork was of uniform thickness in any horizontal plane of such portions of the heating wall all along the coking chamber.

The coking chambers of a coke oven battery are each formed between a spaced pair of flued heating walls of which the masonry comprises, in most modern coke ovens, silica bricks laid in mortar in courses or tiers. The individual bricks of each tier or course, and those of adjacent tiers, are joined by a layer of special mortar 18 having a refractoriness only slightly less than that of the bricks themselves. The material of the silica bricks has a Pyrometric Cone Equivalent (hereinafter referred to as P.C.E.) of about 3000-3056° F. and shows upon chemical analysis a content of approximately 95 to 96% of silica, 2% of lime, and about 2% of such so-called impurities as iron oxide, alumina, and the like. The mortar or cement in which they are customarily set is prepared from silica brickbats, raw ganister, and a silicious clay, the finished mortar containing 92% to 94% of silica, and from 6% to 8% of alumina, iron oxide, lime, etc., and having a P.C.E. of between about 2940° to 3000° F. The P.C.E. of the mortar wherein the silica bricks are set has thus a P.C.E. of not more than about 100° F. lower than the bricks themselves.

If the temperatures of the heating-wall masonry are raised to about 2600°-2700° F., a relatively rapid recrystallization of silica in the mortar as well as that in the bricks begins to take place and crystal growths, extending therebetween and involving forms of silica in the both, are produced and the bricks and mortar become thereby so securely bonded together that the structure of the brick, themselves, frequently yields under stress before the surface of their contacts with the mortar. The extent of such bond follows rather closely the isothermal lines of 2600°-2700° F. in the heating wall.

In accordance with the present invention, the alternate tiers or courses 21 and intermediate tiers or courses 19 of liner bricks that form the liner wall portions 13 between the tie walls 20 are composed, throughout substantially the full height of the combustion flues, of different thickness, the alternate tiers or courses 21 being 2½ to 4½ inch brick and the intermediate tiers 19 being 5 to 8 inch brick, and a mortar joint 18 being provided between the tie wall 20 surface and the adjacent surface of the inwardly projecting 2½ to 3½ inches of the 5" to 8" liner brick.

The many benefits that accrue from the present invention are attained in a better way with the horizontal cok-

ing chamber 10 arranged in a battery with vertical combustion flues 12, as indicated in FIGURES 4 and 5, wherein each horizontal slot chamber 10 and its heating walls 11 are in the form of a battery of a series of alternate coking chambers with a heating wall 11 intermediate each two coking chambers 10 arranged side-by-side in a row. As shown, the liner walls 13 are interconnected, as conventionally, by tie walls 20, which together with the liner walls 13, form the vertical combustion flues 12.

The 5" to 8" brick of the intermediate tiers 19 along the upper half of the flues 12 that are in the portion of the liner walls 13 between each two tie walls 20, project inwardly into the vertical flues about 2½ to 3½ inches, and their side faces are united to the faces of the tie walls 20 by mortar joints 18, as above described. As is shown in FIGURES 4 and 5 the outer surface of each liner wall 13 forming a face for the coking chamber 10 adjacent thereto is substantially a plane surface while the inner surface (flue side) of each liner wall 13 is a furrowed or corrugated surface in which the thicker intermediate tiers 19 appear in FIGURE 4 as a series of alternating horizontally extending ribs and valleys.

Each flue 12 is provided at its lower end with a pair of regenerator ports 22, and an inlet nozzle 23 for rich gas, and a pair of crosswise regenerators 24, and 25, are connected with each flue through their regenerator ports as conventional for "combination" oven underfiring.

Referring to FIGURES 7 to 18, there is shown the manner in which the invention may be utilized in conjunction with the standard brick shapes as used in construction of the three most generally used types of coke ovens.

FIGURES 7 to 10 illustrate the shapes of the bricks, and their employment in conjunction with the present invention, as used in the standard Koppers-Becker and also the H. Koppers ovens. In these drawings 10 indicates the coking chambers, 11 the heating wall between them, and 12 is the combustion flue between two tie walls 20. The liner walls 13 are comprised of alternate courses or tiers 21 and intermediate courses or tiers 19. Numeral 26 indicates the regenerator ducts and 27 the horizontal flue. The bricks are of the type illustrated in Totzek Patent No. 1,782,638. In this type of coking retort oven, each tier is composed of two spaced courses of liner or stretcher brick 40 and an interposed connecting course of tie or header brick 41. The liner brick 40 have recesses 42 at their inner faces for interlocking with the tie brick 41. The tie brick 41 alternate with the liner brick 40 in each course. The tie brick 41 have the shape of a hammer-head 41a which is joined to a transverse brick 41b. The hammerheads 41a for the tie wall 20 alternate in position in the courses on opposite sides of the heating wall 11. The limbs or transverse brick 41b are made of several brick as shown. The brick of the alternate tiers 21 and those of the intermediate tiers 19 are staggered so that the hammerheads 41a are at opposite ends of adjacent tie walls 20 in each tier 19 and 21.

In accordance with the present invention, the liner brick in the intermediate tiers 19 are of greatest thickness so as to protrude into the flue chamber 12, between each two tie walls, for 2½ to 3½ inches. As a consequence, the protruding portions 40c of the liner brick of the intermediate tiers are bonded by the heat of the combustion in the flue chambers 12 to the adjacent bricks of the same tier in the tie walls, through crystallization of the silica mortar of the vertical joints 43, and also likewise bonded through the mortar joints 44 between these bricks and the bricks in the alternate tiers above and below the intermediate tiers, thus providing the greater strength to the wall inherent in such a bond. The protruding portions of the brick in the intermediate tiers are also exposed on three sides, 45, 46, and 47, thus heating these bricks to provide the isotherm as indicated in FIGURE 3.

FIGURES 11 to 14 illustrate the shapes of the bricks, and their employment in conjunction with the present

7 invention, as used in the standard Wilputte double divided ovens. In these drawings 10 likewise indicates the coking chambers, 11 the heating wall between them, and 12 is the combustion flue between two tie walls 20. The liner walls 13 are composed of alternate courses or tiers 21 and intermediate courses or tiers 19, and 26 indicates the regenerator ducts and 27 the horizontal flue. The bricks are of the type illustrated in Otto U.S. Patent No. 2,665,242. In this type of coking retort oven, each tier is composed of two spaced courses of liner bricks 48 and binder or cross tie bricks 49. The liner bricks 48 have recesses 50 at their inner faces for interlocking with the tie brick 49. One end of each course of tie brick 49 consists of a tenon 51 extending between liner bricks 48 in the liner wall area 13 and forming a part thereof. The adjacent superposed tie bricks 49 of the tiers are turned end for end, and have their tenon portions 51 provided with shoulders 52 which overlap the liner brick 48 at their joints. The limbs 53 of the tie brick 49 are made of several bricks. In accordance with this invention, the liner brick in the intermediate tiers 19 are of greater thickness than those in the alternate tiers 21, so as to protrude into the flue chamber area 12, between each two tie walls 20, for 2½ to 3½ inches. As a consequence, the protruding portions 54 of the liner brick 48 of the intermediate tiers or courses 19, are bonded through crystallization of the silica mortar 18 of the vertical joints 55, and also likewise bonded through the mortar joints 56 between these bricks 48 and the bricks 48 in the alternate tiers or courses 21 above and below the intermediate tiers, thus providing greater strength to the wall 13 inherent in such bond. The protruding portions 54 of the brick of the intermediate tiers are also exposed on the three sides, 57, 58, and 59, thus heating these bricks to provide the isotherm as indicated in FIGURE 3.

FIGURES 15 to 18 illustrate the shapes of the bricks, and their employment in conjunction with the present invention as used in the standard Otto twin or hairpin flue ovens. In these drawings, 19 also indicates the coking chambers, 11 the heating wall between them, and 12 is one limb of the hairpin combustion flue between two tie walls 20. The liner walls 13 are composed of alternate courses or tiers 21 and intermediate courses or tiers 19, and 26 indicates the regenerator ducts and 27 the horizontal flow connection between adjacent limbs for concurrent upflow in each limb 12 in alternation with the downflow in the other limb 12. The bricks are also of the type illustrated in Otto U.S. Patent No. 2,665,242. In this type of coking retort oven, each tier is composed of two spaced courses of liner brick 60 and binder or cross tie brick 61. The liner brick 60 have recesses 62 at their inner faces for interlocking with the tie brick 61. One end of the course of tie brick consists of a tenon 63 extending between the ends of liner brick 60 in the liner area 13 and forming a part thereof. The adjacent superposed tie bricks 61 of the tiers are turned end for end, and have their tenon portions 63 provided with shoulders 65 which overlap the liner brick 60 at their joints. The limbs 66 of the tie brick 61 are made of several bricks. In accordance with this invention, the liner brick in the intermediate tiers 19 are of greater thickness than those in the alternate tiers 21, so as to protrude into the flue chamber area 12, between each two tie walls 20, for 2½ to 3½ inches. As a consequence, the protruding portions 67 of the liner brick 60 of the intermediate tiers or courses 19, are bonded through crystallization of the silica mortar 18 of the vertical joints 67, and also likewise bonded through the mortar joints 68 between these bricks 60 and the bricks 60 in the alternate tiers or courses 21 above and below the intermediate tiers, thus providing the greater strength to the wall 13 inherent in such bond. The protruding portions 67 of the brick of the intermediate tiers are also exposed on the three sides 69, 70, and 71, thus heating these bricks to provide the isotherm as indicated in FIGURE 3.

8 The best mode of carrying out the novel feature of the present invention to attain its benefits to greatest extent is in conjunction with the improvements of the aforesaid Patent No. 2,447,837.

5 Accordingly, as shown in FIGURES 4 and 5, the vertical combustion flues 12 of each heating wall 11 constructed according to the invention as aforesaid, are interconnected by cross-over flues and upper horizontal flow ducts 27. Said vertical combustion flues terminate at their 10 upper parts (flow ducts 27) below the top level 29 for leveled coal charges; which level 29 conventionally is the lower level of the leveler door (not shown) in the pusher ram doorway 10a through which the tops of the coal charges are leveled to leave above the top of the leveled coal charge a gas off-flow space 16 along the crown of the oven chambers 10.

In this structure in accordance with the invention of Joseph Becker Patent No. 2,100,762, all regulation is at the bottom of the vertical flues 12 by means of restrictions for the regenerator ports 22 and the rich gas horizontal inlets 23. The areas of the vertical combustion flues 12, flow duct means 27, and cross-over flues for the vertical flues 12 are made sufficiently large that they have no material effect on the gas flow and in this way, the gas 25 flow through the flues occurs with lesser differences in pressure from inlet to outlet, and less draft is required, and the liner walls 13 are vertically disposed throughout the major portion of their height for uniform coking vertically throughout coal charges in the coking chambers 10.

30 In operation, coal is charged into the oven chambers 10 through their top charging holes in the oven roof and leveled at the top level 29, and heat is applied by combustion of gas and air in the vertical flues 12, to maintain substantially the same temperatures all along the heating walls 35 11, except at the end flues where the temperature is higher because of radiation at the opposite side faces of the battery. All the regulation is below the bottoms 15 of the flues and due to the two thicknesses of the liner walls 13 made feasible by the advent of the present invention, the mass of coal is fully coked in a shorter coking time 40 by heat applied laterally inwardly from the sides of the chamber. The faster coking time with the novel liner structure provides for a greater number of charges of coke to be made up to 15% to 20% more than heretofore 45 with liner walls of one thickness.

The invention, as described hereinabove, is embodied in particular form and manner but may be variously embodied within the scope of the claims hereinafter made.

What is claimed is:

50 1. In a horizontal coking retort oven battery, an intermediate heating wall for two adjacent horizontal coking chambers comprising:

- 55 (a) spaced longitudinal brick liner walls,
- (b) intermediate transverse tie walls tying said liner walls and defining therewith individual vertical combustion flues inside the heating wall, and
- (c) alternate and intermediate horizontally disposed layers of bricks in said liner walls arranged to form an outer substantially plane surface and an inner corrugated surface,

(1) the intermediate horizontally disposed layers being substantially thicker than the alternate horizontally disposed layers and projecting inwardly thereof into the vertical flues, the projecting portions thereof extending between adjacent tie walls being bonded thereto.

2. Apparatus as claimed in claim 1, and in which the alternate and intermediate layers each comprise a single 70 course of brick.

3. In a horizontal coking retort oven battery, an intermediate heating wall for two adjacent horizontal coking chambers comprising:

- (a) spaced longitudinal brick liner walls,
- (b) intermediate transverse tie walls tying together said

liner walls and defining therewith individual vertical combustion flues inside the heating wall, and
 (c) alternate and intermediate horizontally disposed strata of bricks in said liner walls arranged to form outer substantially plane surface and an inner corrugated surface,

- (1) the alternate horizontally disposed strata having a maximum thickness in the range from about 2½ inches to about 4½ inches, and
- (2) the intermediate horizontally disposed strata having a maximum thickness in the range from about 5 inches to about 8 inches with portions thereof projecting inwardly into the vertical flues and extending between adjacent tie walls being bonded thereto.

4. In a horizontal coking retort oven for a flue within a heating wall thereof, which flue is defined by liner walls and tie walls, liner wall construction comprising an outer substantially plane surface, an inner corrugated surface of

alternating ribs and valleys, said ribs extending from tie wall to tie wall and being bonded thereto.

5. Liner wall construction substantially as recited in claim 4 wherein the ribs project a maximum of about 3½ inches from the surface of the valleys.

6. Liner wall construction substantially as described in claim 5 wherein the maximum thickness of the liner wall between ribs is within the range of about 2½ to about 4½ inches and the maximum thickness of the liner wall through the ribs is in the range of about 5 inches to about 8 inches.
